(57) **CLAIM**

The ornamental design for a goalie skate as shown and described.

DESCRIPTION

FIG. 1 is a perspective view of the goalie skate;

FIG. 2 is a right-side elevational view thereof;

FIG. 3 is a left side elevational view thereof;

FIG. 4 is a front elevational view thereof;

FIG. 5 is a bottom view thereof;

FIG. 6 is a top view thereof; and,

FIG. 7 is a rear elevational view thereof.

The dashed lines shown in the Figures represent portions of the goalie skate which form no part of the claimed design. The dash-dot lines shown in the figures represent a boundary between claimed and unclaimed portions of the goalie skate.
